CLAIM

The ornamental design for a video brochure, as shown and described.

DESCRIPTION

FIG. 1 is a perspective view of a video brochure;

FIG. 2 is a front view of the video brochure;

FIG. 3 is a rear view of the video brochure;

FIG. 4 is a bottom view of the video brochure;

FIG. 5 is a top view of the video brochure;

FIG. 6 is a right side view of the video brochure; and,

FIG. 7 is a left side view of the video brochure.

The broken lines illustrate portions of the video brochure that form no part of the claimed design.
